AUTOMATIC VARIABLE SPEED CONTROL

Jerry Paul Lesley and Barney Gains Martin,
Easley, S. C.

Application December 14, 1942, Serial No. 468,980

6 Claims. (CL. 242—39)

This invention relates to an automatic variable speed control and stop motion and more particularly to a device of this character in combination with winding and reeling machinery.

For example, after a warp of yarn passes from the drying drums of a slasher, it is wound upon a beam, which beam is driven in timed relation to the operation of the slasher. When the proper amount of yarn has been wound onto the beam, the speed of the slasher is greatly reduced so that the filled beam can be replaced by an empty beam, after which the slasher resumes its full operating speed.

It is very desirable to have substantially the same amount of yarn wound on each beam, and therefore it is necessary for the operator to repeatedly inspect the winding progress, especially as the beam is being completed. If too much material is wound upon the beam, much time and labor are often consumed in correcting this error.

It is therefore an object of this invention to provide an automatic fluid operated mechanism for reducing the speed of a take-up beam and associated mechanism when the material on the beam reaches a predetermined diameter. Such a device permits the operator to engage in a number of other tasks, with the assurance that the beam will not be over-filled within a reasonable length of time after the predetermined diameter has been reached.

Some of the objects of the invention having been stated, other objects will appear as the description proceeds, when taken in connection with the accompanying drawings in which:

Figure 1 is a side elevation of a portion of a slasher, showing the present invention associated therewith;

Figure 2 is an isometric view of certain portions of the present invention associated with the driving mechanism for the slasher;

Figure 3 is a sectional plan view through the right-hand portion of Figure 2, illustrating the structure of the variable speed driving mechanism;

Figure 4 is an enlarged sectional view of the left-hand portion of Figure 1, illustrating a feeler mechanism which is adapted to be actuated by a predetermined diameter of material on the take-up beam for stopping or reducing the speed of the slasher;

Figure 5 is a sectional plan view taken along the line 5—5 in Figure 4, illustrating the structure of a stop-and-waste valve associated with the present invention;

Figure 6 is a sectional plan view similar to Figure 5 but showing the valve turned to waste position;

Referring more specifically to the drawings, the numeral 10 denotes the framework of a slasher, said slasher having lease rods 11, comb 12, delivery roll 14, friction rolls 15 and 16, and take-up beams 17.

The take-up beam is removably mounted upon the framework 10, however, such removable structure is not shown because it does not constitute a part of the present invention. It might be stated, however, that the beam 17 is operatively connected to a gear 18 by any suitable means such as a slip-clutch arrangement, not shown, so that material will be wound upon the beam at a uniform rate regardless of the diameter of the wound material. In operation, a suitable warp of material 19 is adapted to be divided by lease rods 11, after which it passes through comb 12, over friction roll 15, and then under the delivery roll 14. After passing beneath the delivery roll 14, it partially encircles the friction roll 16, from whence it passes to the take-up beam 17. It is evident that the rate of rotation of the beam 17 should gradually diminish as the material builds up on the beam. Therefore, the above-mentioned slip-clutch mechanism, not shown, is employed so that the driving gear 18 may rotate at a uniform rate.

The driving gear 18 meshes with a larger gear 20 on the end of delivery roll shaft 21, said gear 20 being driven by a pinion 22 on cone shaft 23. A suitable cone pulley 24 is fixedly secured upon the shaft 23, and upon this cone pulley, a driving means such as a belt 25 is mounted, which belt is also mounted upon a second cone pulley 26 on a transversely disposed shaft 27. The end of shaft 27, nearest the observer in Figures 1 and 2, is journaled in a suitable bearing 29, the other end of said shaft being journaled in the framework 10. Shaft 27 has a pulley 35 fixedly secured thereto (see Figure 3) upon which a belt 36 is adapted to be mounted. This belt is driven from a suitable source of power, not shown. When the belt 36 is disposed upon the pulley 35, the machine is adapted to operate at full speed, that is, the delivery roll 14 and take-up beam 17 are driven through the medium of members designated by reference characters 18 to 21 inclusive. When it is desired to drive the members 14 and 17 at a reduced speed, the belt 36 is shifted from fixed pulley 35 to an adjoining slow pulley 38 by means of a belt shifter 39.

This shifter has spaced prongs 40 and 41 which are disposed on opposed sides of belt 36.

By observing Figure 3, it can be seen that the pulley 38 is fixedly keyed upon a sleeve 45, which sleeve, in turn, is rotatably mounted upon shaft 27. A gear 46 is also fixedly keyed upon sleeve 45, and this gear meshes with another gear 47 on a shaft 48, said shaft being rotatably mounted in a suitable bearing 49. Shaft 48 has a pinion 50 fixedly secured thereon on the opposed side of the bearing 49 from the gear 47, said pinion 50 being adapted to mesh with a gear 51, loosely mounted around a hub 52 of a ratchet wheel 53.

Extending from the face of gear 51 (see Figure 2) is a pin 55 upon which is rotatably mounted a dog 56. This dog is adapted to engage the teeth in ratchet 53. When the belt 36 is disposed upon the slow pulley 38, the cone pulley 26 (see Figure 3) is driven through the medium of members designated by reference characters 45, 46, 47, 48, 50, 51, 52, 55, and 56. It can be seen that the hub 52 is fixedly keyed upon the shaft 27, therefore, when the gear 51 rotates in a counter clockwise manner in Figure 2, the shaft 27 will also turn because the gear 27 and ratchet wheel 53 are connected by dog 56. On the other hand, when the belt 36 is disposed upon the fixed pulley 35, the parts 45, 46, 47, 48, 50, 51, and 56 will remain stationary and the stationary dog 56 will ratchet over the teeth of rotating wheel 53.

The manual means employed for shifting the belt 36 from one pulley to the other is shown in Figures 1 and 2. It is here seen that the belt shifter 39 is mounted upon a square shaft 60, said shaft being slidably mounted in a bearing 61 secured to the framework 10. In Figure 2, it is seen that a counterweight 64 is provided to balance the weight of the belt shifter 39. Pivottally secured to the shaft 60 as at 65 is a link 66, said link, being pivotally secured as at 67 to a lever 68. This lever is fixedly secured upon a vertically disposed shaft 69, which is mounted for oscillation in bearings 70 and 71. Extending from the shaft 69 is a second lever 75 to which is pivotally secured as at 76 one end of a link 77. The other end of link 77 is pivotally secured as at 78 to the intermediate portion of a hand lever 79, said hand lever having its lower end rotatably mounted in bracket 80 as at 81. Bracket 81 is secured to the framework 10.

When the hand lever 79 is rotated in a clockwise manner in Figures 1 and 2, for example, the belt shifter 39 is moved to the left in Figure 2 to first shift the belt from fixed pulley 35 to the slow pulley 38. If it is desired to completely stop the rotation of delivery roll 14 and take-up beam 17, the hand lever 79 is still farther rotated in a clockwise manner to cause the belt 36 to be moved upon a loose or idler pulley 85 which is rotatably mounted around the sleeve 45 previously described. It is noted that the pulleys 35, 38, and 85 are substantially the same diameter; therefore, belt 36 can be shifted at will manually by operating the lever 79.

A stop collar 86 is adjustably mounted upon the square shaft 60 as at 87. If desired, this collar can be positioned so that the belt shifter 39 cannot shift the belt to the loose pulley 85 when changing the speed of the machine. In other words, the member 86 can be manually set to limit the travel of the belt shifter 39 so that the belt shifter 39 will stop when the belt 36 is moved upon slow pulley 38. Another setting can be made so that the belt can be shifted from fast pulley 35, across slow pulley 38, and onto idler

pulley 85. The position that this collar 86 occupies, of course, determines the stopping position of the belt 36. The above-described parts are conventional in textile slashers, but it is thought desirable to show and describe this much of the conventional structure in order to more clearly set forth the function of the present automatic speed control.

As heretofore stated, it is very desirable to provide automatic means whereby a predetermined diameter of material upon the take-up beam 17 will automatically serve to reduce the speed of the slasher. It is not desirable, in some instances, to completely stop the slasher, because the yarn is being constantly drawn through a size box, not shown, and if its travel is stopped, will have a tendency to gather more than the desired amount of size solution thereon, and consequently, be damaged. It is therefore desirable to provide automatic means for slowing down the speed of the slasher so that the yarn will slowly pass through the size box, but at such a reduced speed that there will be very little likelihood of the take-up beam 17 becoming too full before the operator has an opportunity to replace it with an empty beam.

Specifically the structure for shifting the belt 36 from the fast pulley 35 to the slow pulley 38 comprises a feeler mechanism for engaging the periphery of the yarn on the take-up beam in combination with an air valve operated by the feeler for admitting compressed air into a cylinder. This cylinder is adapted to actuate the belt shifter 39 by means of the mechanism previously described, and which is shown in Figures 1 and 2.

Referring now to Figure 4, it can be seen that a roller 89 is normally disposed at the desired distance from the center of the take-up beam 17. This roller is secured in one end of a lever 90, said lever, in turn, being pivoted intermediate its ends as at 91 to a bracket 92. Bracket 92 is secured to a valve 93, disposed in a pipe line 94, said pipe line having the lower end thereof communicating with a suitable source of compressed fluid, such as a tank of compressed air 98.

The structure for closing the valve 93 comprises a valve head 99 on one end of a valve stem 100, said stem 100 being slidably mounted in the valve and having the projecting end thereof disposed adjacent one end of the lever 90. A spring 101 is normally pressed against the valve head 99 by a nut 102, said spring being adapted to normally hold the valve cap in seated or closed position to prevent air or fluid from escaping upwardly from pipe 94 through the valve.

For example, when the material 19a on take-up beam 17 increases in diameter, from the bold line position shown in Figure 4 to the dotted line position 19b, the roller 89 will be engaged to thereby cause the roller and associated lever 90 to be rotated to dotted line position. When this rotation is imparted, the lower end of the lever 90 will engage the projecting end of valve stem 100 and move the valve stem and associated valve head 99 to the left in Figure 4, thereby unseating the valve head and permitting the fluid under pressure to flow upwardly from tank 98 through pipe 94 and then through the valve 93. The fluid which is permitted to escape upwardly through the valve 93 serves to automatically transfer the belt 36 from the fast pulley 35 to the adjacent slow pulley 38, or if the proper adjustment of stop collar 86 is made, the belt 36 will be auto-

matically shifted to idler pulley 85. The mechanism operated by the escaping fluid under pressure for accomplishing this automatic belt shifting will now be described.

Connected to the upper end of valve 93 is a pipe 105 and this pipe has its other end connected to a stop-and-waste valve 106. The stop-and-waste valve has a conical plug 107 rotatably mounted therein, said plug having a handle 108 connected to one end thereof for operating the same. A transverse bore 109 is disposed in the plug, and this bore is adapted to communicate with aligned bores 110 disposed on each side thereof when the material is being wound upon the take-up beam 17. Leading from the opposite end of the valve 106 from the end communicating with pipe 105 is a conduit or hose 111. This hose has its other end communicating with a compression compartment 112 of a cylinder 114, said cylinder having a piston 115 slidably mounted therein. Connected to the piston and extending longitudinally through a bore 116 in the other end of the cylinder is a rod 117. This rod (Figure 2) is pivotally secured as at 118 to the free end of a laterally extending lever 119, which lever is fixedly secured to the vertically disposed shaft 69 previously described.

It is therefore seen that the fluid under pressure which escapes upwardly through the valve 93 and into pipe 105 will enter the chamber 112 of cylinder 114. This fluid will move the piston 115 to the right in the cylinder and at the same time move the rod 117 in a similar manner to automatically rotate the shaft 69 and lever 68 to cause the belt shifter 39 to shift belt 36 in the manner previously described. As heretofore stated, when the belt has been shifted to the slow pulley, the movement of the warp 19 and the take-up beam 17 will be very slow, and therefore, the operator can replace the filled beam 17 with an empty beam without changing the speed of the mechanism. If for any reason, it should be desired to automatically stop the mechanism when the beam reaches a predetermined size such as 19b, it would only be necessary to adjust the collar 86 in such a position on the square shaft 60 that a greater longitudinal movement of the shaft 60 and belt shifter 39 will be permitted, to permit the belt 36 to shift from the fast pulley 38, over the slow pulley 38, and onto the idler pulley 85.

After the delivery roll 14 and associated take-up beam have been slowed down or stopped, and after a filled beam has been replaced by an empty beam, it is then desired to resume the top operating speed. In order to do this, it is necessary to release the trapped air or fluid under pressure in the compression compartment 112 to permit the piston 115 and associated connecting rod 117 to be moved back to normal position and thus allow the belt shifter 39 and associated belt 36 to be again positioned upon the fast pulley 38. The exhaust of the fluid from compartment 112 is effected by the stop-and-waste valve 106. It is seen that the plug 107 has a port 120 therein which is disposed at substantially right angles to the port 109 previously described. When material is being wound upon the take-up beam, the ports 109 and 120 occupy the position shown in Figures 4 and 5; whereas when the mechanism is resuming top speed, the ports are shifted from the position shown in Figure 5 to the position shown in Figure 6. At this time, the fluid supply from the pipe 94 and tank 96 is cut off by the valve, but the fluid from the compression

compartment 112 is permitted to exhaust by way of a conduit 111, port 110, port 109, and an exhaust port 121 in the valve 106. With the fluid exhausted from the compression compartment 112, the operator can then manually operate the handle 79 to reposition the belt 36 upon the desired pulley.

As a means for lubricating the interior of the cylinder 114 and the piston 115, a suitable port 123 is provided in the cylinder.

After the parts have been returned to operating position with the belt on the tight pulley 35, the stop-and-waste valve plug 107 is returned to the position shown in Figure 4, so that when the beam is again filled with yarn, the compressed fluid can pass into compartment 112 when valve head 99 is opened by the feeler mechanism.

In the drawings, an automatic mechanism arrangement has been shown particularly adapted to be pneumatically operated. It is to be understood, however, that the present apparatus is not restricted to the use of air, because many other suitable fluids under pressure may be employed with good results, such as water, oil, and the like.

In the drawings and specification, there has been set forth a preferred embodiment of the invention, and although specific terms are employed, they are used in a generic and descriptive sense only and not for purposes of limitation, the scope of the invention being defined in the claims.

We claim:

1. In combination with a beam having means for rotating the same to wind a web of material such as yarn, cloth, or the like thereon, a feeler engageable with the material on said beam when the material reaches a predetermined diameter, a pressure cylinder, a piston slidably mounted in said cylinder, a compressed air supply, means operable by said feeler, when engaged, for admitting compressed air from said supply into said cylinder to move said piston, means operable by said piston for reducing the rate of rotation of said beam, and a stop-and-waste valve disposed between said air supply and said cylinder whereby the air from said supply may be cut off simultaneously with the exhaustion of the air from said cylinder.

2. In combination with a beam having means for rotating the same to wind material such as yarn, cloth, and the like thereon, a feeler engageable with the material on said beam when the material reaches a predetermined diameter, a pulley for driving said beam at one speed, a second pulley for driving said beam at a reduced speed, a third loose pulley, a belt adapted to engage said pulleys one at a time, and fluid operated means controlled by said feeler for transferring said belt from the first pulley to one of the other pulleys when the material on said beam reaches said predetermined diameter.

3. In combination with a beam having means for rotating the same to wind material such as yarn, cloth and the like thereon, a feeler engageable with the material on said beam when the material reaches a predetermined diameter, a pulley for driving said beam at one speed, a second pulley for driving said beam at a reduced speed, a belt adapted to engage said pulleys one at a time, a pressure cylinder, a piston slidably mounted in said cylinder, a compressed air supply, means operable by said feeler when engaged, for admitting compressed air from said supply

into said cylinder to cause said piston to slide, and means operated by said piston for transferring said belt from the first pulley to the second pulley when the material on said beam reaches said predetermined diameter.

4. In combination with a beam having means for rotating the same to wind material such as yarn, cloth and the like thereon, a feeler engageable with the material on said beam when the material reaches a predetermined diameter, a pulley for driving said beam at one speed, a second pulley for driving said beam at a reduced speed, a belt adapted to engage said pulleys one at a time, a pressure cylinder, a piston slidably mounted in said cylinder, a compressed air supply, means operable by said feeler when engaged, for admitting compressed air from said supply into said cylinder to cause said piston to slide, means operated by said piston for transferring said belt from the first pulley to the second pulley when the material on said beam reaches said predetermined diameter, and a stop-and-waste valve disposed between said air supply and said cylinder whereby the air from said supply may be cut-off simultaneously with the exhaustion of the air from said cylinder.

5. In combination with a beam having means for rotating the same to wind material such as yarn, cloth, and the like thereon, a feeler engageable with the material on said beam, when the material reaches a predetermined diameter, a pulley for driving said beam at one speed, a second pulley for driving said beam at a reduced speed, a belt adapted to engage said pul-

leys, one at a time, a pressure cylinder, a piston slidably mounted in said cylinder, a supply of fluid under pressure, means operable by said feeler when engaged, for admitting said fluid under pressure from said supply into said cylinder to cause said piston to slide, and means operated by said sliding piston for transferring said belt from the first pulley to the second pulley when the material on said beam reaches said predetermined diameter.

6. In combination with a beam having means for rotating the same to wind material such as yarn, cloth, and the like thereon, a feeler engageable with the material on said beam, when the material reaches a predetermined diameter, a pulley for driving said beam at one speed, a second pulley for driving said beam at a reduced speed, a belt adapted to engage said pulleys one at a time, a pressure cylinder, a piston slidably mounted in said cylinder, a supply of fluid under pressure, means operable by said feeler when engaged, for admitting said fluid under pressure from said supply into said cylinder to cause said piston to slide, means operated by said sliding piston for transferring said belt from the first pulley to the second pulley when the material on said beam reaches said predetermined diameter, and a stop-and-waste valve disposed between said supply and said cylinder whereby the air from said supply may be cut off simultaneously with the exhaustion of the air from said cylinder.
